UNITED STATES PATENT OFFICE.

BENJAMIN F. MAYO, OF SALEM, MASSACHUSETTS, ASSIGNOR TO UNITED SHOE MACHINERY COMPANY, OF PATERSON, NEW JERSEY, A CORPORATION OF NEW JERSEY.

STOP MECHANISM.

1,091,071.

Specification of Letters Patent. Patented Mar. 24, 1914.

Application filed November 7, 1902. Serial No. 130,385.

To all whom it may concern:

Be it known that I, BENJAMIN F. MAYO, a citizen of the United States, residing at Salem, in the county of Essex and State of Massachusetts, have invented certain new and useful Improvements in Stop Mechanisms; and I do hereby declare the following to be a full, clear, and exact description of the invention, such as will enable others skilled in the art to which it appertains to make and use the same.

The present invention relates to an improved stop mechanism particularly designed for use in connection with sole rounding machines but which is also capable of use in other relations.

The object of the invention is to improve the construction, arrangement and mode of operation of the various parts of stop mechanisms and more particularly of stop mechanisms of that type which, when applied to a sole rounding machine, are adapted to allow a relative movement of the pattern and rounding knife due to the momentum of the various operating parts of the machine after the driving shaft has been disconnected from the source of power and to thereafter return the pattern and knife to normal position.

The novel features of my improved stop mechanism consist in the improved mechanism for disconnecting the driving shaft from the source of power and stopping the rotation of the shaft, in the construction and arrangement of the means which allows a forward movement of the mechanism driven from the driving shaft after the driving shaft is disconnected from the source of power and which imparts a return movement to such mechanism, and in certain details of construction hereinafter specifically described.

A stop mechanism embodying a preferred form of my invention is illustrated in the accompanying drawings as applied to a sole rounding machine of a type well known in the art.

Referring to the drawings, Figure 1 is a view in side elevation of a preferred form of my improved stop mechanism, a portion only of the rotary support for the knife carrier of the sole rounding mechanism being shown; Fig. 2 is a plan view of the mechanism illustrated in Fig. 1; Fig. 3 is a longi-

tudinal sectional view on the line 3—3 of Fig. 2; Fig. 4 is a view of the mechanism illustrated in Figs. 1 and 2 looking from the left, the rotary support being omitted; Fig. 5 is a sectional view on the line 5—5 of Fig. 2; Fig. 6 is a plan view of a lever forming a portion of the mechanism for stopping and starting the driving shaft; Fig. 7 is a detail view in side elevation of one end of the driving shaft illustrating the construction which allows a forward movement of the rotary support independent of the driving shaft when the driving shaft is stopped and which returns the rotary support to its normal position with relation to the driving shaft; Fig. 8 is a detail sectional view on the line 8—8 of Fig. 7; Fig. 9 is an end view of the beveled gear by which the rotary support is driven from the driving shaft; Fig. 10 is an end view of the collar secured to the driving shaft which engages the beveled gear illustrated in Fig. 9; Fig. 11 is a view in side elevation, and Fig. 12 is a view in end elevation of a stationary cam disk forming a portion of the mechanism for moving the clutch members out of engagement; Fig. 13 is a view in side elevation, and Fig. 14 is a view in end elevation of a disk also forming a portion of the mechanism for moving the clutch members out of engagement; and Figs. 15 and 16 are views in plan and side elevation of the trip by which the latch which holds the mechanism for moving the clutch members out of engagement and stopping the rotation of the driving shaft is operated.

Referring to the drawings *a* designates a driving shaft journaled in a bracket *a'* secured to the frame of the machine. On one end of the driving shaft is mounted a beveled gear *b* which meshes with beveled gear *c* formed upon the lower surface of the table of the sole rounding machine upon which the knife carrier is supported. The beveled gear *b* is connected to the driving shaft so as to transmit the movement of the shaft to the rotary support, the connection being such that the gear is allowed to rotate through a part of a revolution after the driving shaft is brought to rest and is then returned to its normal position with relation to the shaft. This independent movement of the beveled gear allows the rotary support to move far enough to carry the round-

ing knife beyond the point of the pattern at which the rounding operation commenced and then to return the rounding knife to such point. The movement of the rounding knife completely around the pattern is thus insured and any liability of leaving a portion of the sole untrimmed is avoided. To allow the beveled gear b to move independently of the driving shaft as above described it is loosely mounted upon the shaft and connected therewith by means of a clutch projection b' on its hub which is engaged by a clutch projection d' on a block or collar d pinned to the shaft. The beveled gear b is thus caused to rotate with the shaft by the engagement of the clutch projections and is allowed to rotate independently of the shaft in the direction in which it is driven, through a portion of a revolution. A split collar e is clamped upon the block d and is connected to the gear b by means of a spring f coiled around the block d and the hub of the gear. One end of the spring f is received in a recess b^2 in the hub of the gear b and the other end is received in a recess e' in the collar e . By adjusting the collar e circumferentially around the block d the tension of the spring can be adjusted as desired. When the gear b is rotated by the continued movement of the rotary support after the driving shaft has been stopped the spring f returns the rotary support and the gear to their normal position. The arrangement of the spring f and the clutch projections on the hub of the gear b and on the block d allows a considerable range of movement to the rotary support after the driving shaft has been stopped. In order to cushion the blow which the clutch projection b' delivers to the clutch member d' when the beveled gear b is returned to normal position by the spring f , the adjacent surfaces of the clutch projections are curved as illustrated in Figs. 8, 9 and 10 and a series of flat spring plates d^3 is interposed between these surfaces. The ends of these plates extend into a recess d^4 in the block d and are held in position by means of a pin d^5 seated in the block d and passing through holes in the plates.

The driving shaft is rotated by means of a driving pulley g loosely mounted upon a sleeve g' which is loosely mounted upon the hub of a wheel or disk h secured to the shaft. The pulley g and wheel h are provided with clutch members by which the rotation of the pulley g is transmitted to the wheel h and to the driving shaft. The sleeve g' is mounted to move longitudinally of the shaft a and the pulley is caused to move with the sleeve by means of a flange g^2 on the sleeve which bears against one end of the hub of the pulley and by means of a flange on the block i mounted to slide longitudinally on the shaft a which flange bears against the other end of the hub of the pulley and against the end

of the sleeve g' . The sleeve g' is moved to bring the clutch members on the pulley g and shaft h into engagement by means of a coiled spring j interposed between the flange of the block i and a block k pinned to the driving shaft.

For moving the sleeve g' in a direction to disengage the clutch members on the pulley g and wheel h and for stopping the rotation of the driving shaft, spring-actuated mechanism is provided which is held out of operation by means of a latch and which is thrown into operation by means of a trip actuated from the driving shaft which contacts with the latch. This mechanism may be described as follows:—Mounted in a recess in the hub of the wheel h are two disks l and m , both disks being free to move longitudinally of the shaft. The disk l , shown separately in Figs. 13 and 14, is provided with two pins l' which pass through holes in the wheel h and bear against the flange g^2 of the sleeve g' . A lever n is pivotally mounted upon a projecting bushing a^2 which forms one of the bearings for the shaft a . In the hub of this lever two pins n' are loosely mounted upon diametrically opposite sides of the driving shaft. At one end these pins bear against cam surfaces formed upon a disk or collar n^2 clamped upon the bushing a^2 , and at the other end bear against the disk m . The arrangement of the pins n' and the cam surfaces of the disk n^2 are such that a movement of the lever n in one direction forces the pins against the disk m and thereby moves the disks m and l in a direction to actuate the sleeve g' to disconnect the clutch members on the pulley g and wheel h while a return movement of the lever allows the spring j to move the sleeve g' in a direction to bring the clutch members on the pulley g and wheel h into engagement.

It will be noted that the means for moving the pulley g in both directions act upon the sleeve g' . The pulley is thus allowed to rotate freely upon the sleeve g' when the clutch members are disconnected, the sleeve being held stationary by the frictional engagement therewith of the pins l' and block i .

The wheel h is provided with a braking member h' with which two braking shoes h^2 are arranged to coöperate to stop the rotation of the driving shaft when the clutch members on the pulley g and wheel h are disengaged. These braking shoes are secured to arms h^3 pivotally mounted on opposite sides of the driving shaft and are connected by links h^4 to the hub of the lever n , the pivotal connection between the links and the hub of the lever being formed by the pins n' which pass through the links. The arrangement of the arms h^3 and the links h^4 is such that the brake shoes h^2 are brought into contact with the braking member h' .

when the lever n is moved in a direction to disengage the clutch members. The lever n is moved in a direction to disconnect the clutch members and to bring the brake shoes into contact with the braking member by means of a spring o coiled around a rock shaft o' journaled in the bracket a' . One end of this spring is secured to a block o^2 fast on the rock shaft o' and the other end is secured to a disk o^3 loosely mounted upon the rock shaft and held from rotation by means of a pin o^4 seated in the bracket a' and extending into one of a series of holes in the disk. The pin o^4 and the disk o^3 serve as a convenient means for adjusting the tension of the spring o . The block o^2 is connected by means of a link o^5 to one end of the lever n , the arrangement being such that a rotation of the shaft o' by the spring o moves the lever n in a direction to disengage the clutch members and bring the brake shoes into contact with the braking member. The lever n is held in the position to which it is moved to connect the clutch members and move the brake shoes out of contact with the braking members by means of a latch p pivotally mounted upon the lever n and arranged to engage a fixed stop p' . The latch p is actuated to release the lever by means of a trip r carried by the rotary support for the knife carrier which as the rotary support completes its revolution engages the end of a lever s secured to a pin s' journaled in the bracket a' , a pin s^2 projecting laterally from the lower end of the pin s' contacting with the latch p when the lever s is actuated by the trip and moving the latch out of engagement with the stop p' . A stop pin s^3 projecting between two laterally extending arms of the lever s serves to limit the movement of the lever s in both directions. The latch p is connected by means of a link p^2 to a lever p^3 pivotally mounted upon the lever n and provided with an arm p^4 integral therewith extending beneath the end of the lever n in convenient position to be grasped by the hand of the operator. The latch p can thus be moved out of engagement with the stop p' by the operator at any time and the rotation of the shaft a stopped. Also pivoted to the lever n is a lever p^5 which extends upward through a slot in the lever in convenient position to be depressed by the hand of the operator. A spring p^6 connects the lever p^5 with the arm p^4 of the lever p^3 and serves to hold the lever p^5 above the surface of the lever n . When the lever n is moved by the operator in a direction to remove the brake shoes from the braking member h' and allow the clutch members to move into engagement, the lever p^5 is pressed down by the hand of the operator and the latch p is yieldingly pressed toward the stop p' by the action of the spring p^6 on the arm p^4 . The trip r which contacts

with the lever s is pivotally mounted upon a plate r' which is received in a groove r^2 in the lower surface of the rotary support upon which the knife carrier is mounted and clamped therein in any desired position. The trip r is normally held in position to contact with the lever s by means of a spring r^3 and is so mounted that it is held rigidly from movement when it contacts with the lever s during the forward movement of the rotary support but is allowed to yield in case the return movement of the rotary support is sufficient to bring it again into contact with the lever.

In the operation of the stop mechanism above described, it will be noted that the driving shaft rotates in one direction only, the means which allows the forward movement of the mechanism driven by the driving shaft after the shaft has been disconnected from the source of power and which imparts a return movement to said mechanism being arranged to act on said mechanism without imparting a return movement to the driving shaft. So far as I am advised of the state of the art, in all stop mechanisms of this type which have heretofore been devised, the means for imparting a return movement to the mechanism driven by the driving shaft has been arranged to act upon the driving shaft and to impart a return movement thereto. By arranging the means for imparting a return movement to the mechanism driven by the driving shaft so as to act on said mechanism without imparting a return movement to the driving shaft, a greater forward and return movement can be imparted to said mechanism than has heretofore been possible.

It will also be noted that the trip which is driven from the driving shaft merely operates to release the mechanism for separating the clutch members and moving the brake shoes into contact with the braking member and is not utilized to actuate such mechanism. The continued movement of the trip, therefore, after the driving shaft has been stopped does not tend to stop the continued rotation of the rotary support and consequently a greater forward and return movement is imparted to the rotary support than would be the case if the trip were utilized to actuate the mechanism for disconnecting the clutch members and stopping the rotation of the shaft.

The operation of the stop mechanism will be readily understood from the preceding description and a separate description thereof is deemed unnecessary.

Having thus indicated the nature and scope of my invention and having specifically described a preferred form thereof, I claim as new and desire to secure by Letters Patent:—

1. A stop mechanism, having, in combina-

tion, a shaft, means for actuating said shaft, means for connecting and disconnecting said shaft and its actuating means and stopping said shaft mechanism driven by said shaft, and a spring connection between said shaft and said mechanism arranged to allow an independent substantial forward movement of said mechanism and to impart a return movement thereto after said shaft is stopped, substantially as described.

2. A stop mechanism, having, in combination, a shaft, means for actuating said shaft, means for connecting and disconnecting said shaft and its actuating means, a gear driven by said shaft, means for imparting a positive forward movement to said gear from the shaft, and a spring connection between said shaft and said gear arranged to allow an independent substantial forward movement of the gear and to impart a return movement thereto, substantially as described.

3. A stop mechanism, having, in combination, a shaft, a gear loosely mounted upon said shaft provided with a clutch projection, mechanism driven by said gear, a collar secured to said shaft provided with a co-operating clutch projection, a spring coiled around said shaft connecting said collar and gear and arranged to allow an independent substantial forward movement of said gear, means for actuating said shaft, and means acting automatically to disconnect said shaft from its actuating means and stop the rotation of said shaft, substantially as described.

4. A stop mechanism, having, in combination, a shaft, mechanism driven by said shaft, a spring connection between said shaft and said mechanism arranged to allow an independent forward movement of said mechanism and to impart a return movement thereto, an independent cushion device for stopping the return movement of said mechanism, means for actuating said shaft, and means acting automatically to disconnect said shaft from its actuating means and stop the rotation of said shaft, substantially as described.

5. A stop mechanism, having, in combination, a shaft, a gear loosely mounted upon said shaft provided with a clutch projection, a collar secured to said shaft provided with a co-operating clutch projection, a cushion device interposed between said projections, a spring connecting said shaft and gear, means for actuating said shaft, and means acting automatically to disconnect said shaft from its actuating means and stop the rotation of said shaft, substantially as described.

6. A stop mechanism, having, in combination, a shaft, means for actuating the same, mechanism driven by said shaft, a spring connection between said shaft and said mechanism arranged to allow a substantial

forward movement of said mechanism with relation to said shaft after the shaft is stopped and to impart a return movement thereto, and means acting automatically to disconnect said shaft from its actuating means and stop the rotation of said shaft, substantially as described.

7. A stop mechanism, having, in combination, a shaft, means for actuating the same, spring-actuated mechanism for disconnecting said shaft from its actuating means and stopping the rotation of said shaft, a latch for said mechanism, a trip actuated by said shaft arranged to actuate said latch and release said mechanism, mechanism driven by said shaft and a spring arranged to allow a substantial forward movement of said mechanism independent of the shaft and to impart a return movement thereto, substantially as described.

8. A stop mechanism, having, in combination, a shaft, a braking member driven by said shaft, a brake, means for actuating said shaft comprising relatively movable clutch members, spring-actuated mechanism for separating said clutch members and applying said brake to said braking member, a latch for said mechanism, a trip actuated by said shaft, arranged to actuate said latch and release said mechanism, mechanism driven by said shaft and a spring arranged to allow a forward movement of said mechanism and to impart a return movement thereto, substantially as described.

9. A stop mechanism, having, in combination, a shaft, means for actuating the same comprising clutch members movable toward and from each other a brake and mechanism thrown into operation by the shaft for separating said clutch members and applying said brake comprising a lever mounted concentrically with said shaft, pins mounted to slide in said lever, a cam engaging said pins and connections between said pins and said clutch members, substantially as described.

10. A stop mechanism, having, in combination, a shaft, a clutch member secured to said shaft, a brake a sleeve, a clutch member mounted loosely upon said sleeve, a disk driven by said first-mentioned clutch member provided with pins bearing against said sleeve, and mechanism thrown into operation by the shaft for actuating said disk to move said sleeve in a direction to separate said clutch members and for applying said brake, substantially as described.

11. A stop mechanism, having, in combination, a shaft, a clutch member secured to said shaft, a brake, a sleeve, a clutch member mounted loosely upon said sleeve, a disk driven by said first-mentioned clutch member provided with pins bearing against said sleeve, mechanism thrown into operation by the shaft for actuating said disk

- to move said sleeve in a direction to separate said clutch members, and for applying said brake comprising a lever mounted concentrically with said shaft, pins mounted to slide in said lever, and a cam engaging said pins, substantially as described. 5
12. A stop mechanism, having, in combination, a shaft, means for actuating the same comprising relatively movable clutch members, a braking member driven by said shaft, brake shoes arranged to engage said braking member, and means for separating said clutch members and bringing said brake shoes into engagement with said 10 braking member comprising a lever mounted concentrically with said shaft, connections between said lever and said clutch members, and links connecting said lever and said brake shoes, substantially as described. 15
13. A stop mechanism, having, in combination, a shaft rotating in one direction only, means for stopping said shaft, mechanism driven by said shaft, and means for allowing an independent substantial forward movement of said mechanism and for imparting a return movement thereto after said shaft is stopped, substantially as described. 20
14. A stop mechanism, having, in combination, a shaft, mechanism driven by said shaft, a spring connection between said shaft and said mechanism arranged to allow an independent substantial forward movement of said mechanism and to impart a return movement thereto and an independent cushion device for stopping the return movement of said mechanism, substantially as described. 25
15. A stop mechanism, having, in combination, a shaft, means for actuating said shaft means for connecting and disconnecting said shaft and its actuating means, a gear driven by said shaft, means for imparting a positive forward movement to said gear from said shaft, a spring connecting the gear and shaft arranged to allow an independent substantial forward movement of the gear and to impart a return movement thereto, and means for adjusting the tension of the spring, substantially as described. 30
16. A stop mechanism, having, in combination, a shaft, means for actuating said shaft, means for connecting and disconnecting said shaft and its actuating means, a bevel gear mounted on the shaft, means for imparting a positive forward movement to said gear from the shaft, a rotary table provided with a bevel gear meshing with the bevel gear on the shaft, and a spring connecting the bevel gear and shaft arranged to allow an independent substantial forward movement of the gear and table and to impart a return movement thereto, substantially as described. 35
17. A stop mechanism having in combination, a shaft and means for rotating the shaft in one direction only, means for stopping said shaft, mechanism to be driven by said shaft, driving means between the shaft and said mechanism embodying devices which drive the mechanism positively in one direction while the shaft is rotating and yet permit the momentum of the mechanism when the shaft is stopped to carry the mechanism a substantial distance forward and then overcome the momentum and resiliently return the mechanism to initial position while the shaft is still at a stand-still. 40
18. A stop mechanism having in combination, a shaft and means for rotating the shaft in one direction only, mechanism to be driven by said shaft, driving means between the shaft and said mechanism embodying devices which drive the mechanism positively in one direction while the shaft is rotating and yet permit the momentum of the mechanism when the shaft is stopped to carry the mechanism a substantial distance forward and then overcome the momentum 45 and resiliently return the mechanism to initial position while the shaft is still at a stand-still, said devices embodying a gear mounted on and driven by the shaft and a spring connection between said shaft and said gear. 50

In testimony whereof I affix my signature, in presence of two witnesses.
